CLAIM

I claim the ornamental design for a container and closure, as shown and described.

DESCRIPTION

FIG. 1 is a front elevational view of a container and closure in accordance with the present invention;

FIG. 2 is a top plan view thereof;

FIG. 3 is a bottom plan view thereof;

FIG. 4 is a front elevational view of a second embodiment of a container and closure showing my new design;

FIG. 5 is a top plan view thereof; and,

FIG. 6 is a bottom plan view thereof.
